UNITED STATES PATENT OFFICE.

ANDREW W. NELSON, OF TERRE HAUTE, INDIANA, ASSIGNOR TO COLUMBIAN ENAMELING & STAMPING COMPANY, OF TERRE HAUTE, INDIANA, A CORPORATION OF INDIANA.

KETTLE-COVER FASTENING.

No. 823,071.

Specification of Letters Patent.

Patented June 12, 1906.

Application filed October 9, 1905. Serial No. 282,025.

To all whom it may concern:

Be it known that I, ANDREW W. NELSON, a citizen of the United States, residing at Terre Haute, in the county of Vigo and State 5 of Indiana, have invented a certain new and useful Improvement in Kettle-Cover Fastenings, of which the following is a specification.

My invention relates to kettle-cover fastenings or mechanism by means of which a detachable cover may be temporarily secured upon a receptacle which it is designed to cover, these conditions being best illustrated in an ordinary stove-kettle, which it is necessary to cover and uncover during the operation of cooking and to lift up from time to time and place in different positions or tilt for pouring contents.

The object of my invention is to provide mechanism of the class described which can 20 be easily and cheaply manufactured and installed, which is efficient in operation, and is not readily liable to get out of order.

My invention consists in a novel mechanism for detachably securing a cover to the 25 kettle or other receptacle in such a way that it can readily be detached, and when the receptacle with the cover upon it is lifted the cover is more firmly fastened upon the receptacle or kettle as increased lifting force is 30 applied at the proper point, and in which even though lifting force be applied at an improper point the cover cannot readily be detached from engagement with the receptacle or kettle.

35 My invention more narrowly consists in the use of two handles, one permanently attached to the kettle-cover and the other bearing upon this first handle and having a connection with the mechanism engaging the 40 side of the kettle, so that lifting the detachable handle serves to clamp the locking mechanism, and also so that on lifting the permanent handle the detachable handle is not disturbed in a way to disengage the locking 45 mechanism.

My invention also consists in details of construction to be hereinafter more fully described and claimed.

50 In the drawings, Figure 1 is a vertical central sectional detail view through mechanism illustrating my invention in its preferred form. Fig. 2 is a corresponding view of Fig.

1, showing the position of the parts when the device is ready to have the cover removed. Fig. 3 is a detail perspective view of the locking mechanism removed from both the kettle 55 and the cover.

Again referring to the drawings the numeral 10 indicates the bottom, and the numeral 11 the wall of any receptacle to which 60 it is desired to apply the mechanism to my invention, in the most common case, as heretofore stated, a kettle for use upon an ordinary cook-stove.

For best results some sort of a flange 12 65 should be provided upon the edge of the kettle, on which the locking mechanism, to be hereinafter described, can find ready engagement. A well-roughened surface or holes in the edge of the wall of the kettle or other receptacle might be used for this purpose without departing from my invention. For this kettle just described I provide a cover 14 of ordinary construction adapted to fit over the edge or rim or flange 12 of the 70 kettle and substantially close the top of the kettle in the ordinary manner, in which such covers have for a long time been used in kitchens and elsewhere. Upon the top of this cover and preferably at approximately its 75 center I provide a stationary handle 15, and at one edge of the cover I provide a hook or hooks 17 or other suitable gripping means adapted to engage the flange 12 or roughened edge or hole or holes cut in the edge of the 80 kettle, as heretofore described.

In the particular construction here illustrated these gripping members or hooks 17 and the permanent handle 15 are made of one piece of wire 18, secured to the top of the 90 cover by the straps 20, passing around the wire 18 and through suitable slots in the cover 14, as shown. This method of securing the wire 18, bearing the handle 15 and the gripping means 17, to the cover is not a part of 95 my invention, and it is entirely immaterial how such attachment is made.

I also provide an independent detachable member consisting of, first, a gripping means, such as hook or hooks 22, adapted to engage 100 in any of the manners heretofore described the edge of the kettle at a point opposite to the gripping mechanism 17, heretofore described; second, a gripping-handle 23, adapt-

ed to normally fit against the permanent handle 15, heretofore described, and upon the side thereof toward the gripping means 17, heretofore described, and upon the opposite side of the handle 15 from the gripping mechanism 22, heretofore described, and, third, long wires 25 or other suitable means connecting this handle 23 and the gripping mechanism 22, these wires normally passing under the handle 15, as shown.

The parts heretofore described are assembled as shown in the figures, from which it will readily be seen that when the operator takes hold of the movable handle 23 and lifts up upon the same, thereby moving it to the dotted-line position in Fig. 1, tension is brought to bear upon the wires 25, with the result that as the handle 23 is lifted the gripping mechanisms 17 and 22 are drawn toward each other, (the handle 23 bearing against the handle 15,) and these mechanisms thereby tightly grip the edge of the kettle, and that the more lifting force there is applied to the handle 23 the tighter these gripping means 17 and 22 will be fastened upon the edge of the kettle, this irrespective of whether said gripping means engage such a flange 12 as is shown or whether they engage a roughened edge of the kettle or holes in the bare edges thereof, as heretofore described.

In view of the foregoing it will readily be seen that as long as lifting force is applied to the handle 23, thereby retaining it in the dotted-line position of Fig. 1, or approximately that position, the cover cannot be detached from the kettle. When the operator releases his or her grip upon the handle 23 in the dotted-line position of Fig. 1 and moves it down to the full-line position, it will be seen that the gripping mechanisms 17 and 22 still loosely retain their hold upon the edge of the kettle and that the operator may take hold of the handle 15 and lift or tilt the kettle without, so long as he or she holds the movable handle in the vertical full-line position of Fig. 1, disengaging the kettle-cover from the kettle. It is not designed that the kettle shall be lifted in this way; but this safety feature is considered an advantage in the event of lifting being accidentally attempted by means of the handle 15. When now it is desired to remove the kettle-cover from the kettle, the operator, with the parts in the full-line position of Fig. 2, takes hold of the handle 23 and gives it a tilting motion toward the left, thereby rotating the entire member 22 25 23 about the handle 15 to the position of Fig. 2, thus moving the gripping means 22 away from the edge of the kettle and releasing the hold of the mechanism upon the edge of the kettle.

By the particular construction here shown I am able to make this device very cheaply of few and inexpensive parts, largely of wire,

so that the device may be applied to old as well as new kettle-covers.

It will readily be seen that by this mechanism when properly used the person operating the device may lift a kettle full of hot liquid or other materials from the stove and tilt the same for pouring without grasping the edge of the kettle and without danger of the kettle being detached from the cover in the operation of lifting or tilting, thereby endangering the operator by the spilling of the hot contents of the kettle or other receptacle.

Having thus described my invention, what I claim as new, and desire to secure by Letters Patent, is—

1. In mechanism of the class described, in combination with the receptacle to be covered and a cover for the same; gripping means on one side of the cover adapted to engage the edge of the receptacle to be covered, a normally stationary handle rising from approximately the center of the receptacle-cover, and an independent member comprising; a handle for the center of the cover, means for engaging the edge of the receptacle and connecting means between the same and said handle; said independent member passing under and bearing against said stationary handle in such a way that as the second handle is lifted the gripping means connected with it is forced into engagement with the edge of the receptacle opposite to said first gripping means whereby said cover is held upon the receptacle.

2. In combination with a kettle and cover for the same; a stationary handle at the center of the cover and gripping means at one edge of the cover, said stationary handle and gripping means being formed from one piece of wire permanently secured to the cover by any suitable means; and an independent member also made of one piece of wire composed of gripping means adapted to engage the kettle on the opposite side from said first gripping means, wires extending from said last gripping means toward and under said permanent first handle and a movable second handle adapted to bear against said first handle on the opposite side of said first handle from said second gripping means; the whole being arranged as shown and described; so that lifting upon the movable second handle clamps the cover upon the kettle or receptacle and releasing the hold upon the said movable handle and tilting said independent member about the first handle releases the gripping mechanism as described so that the cover may be removed from the kettle.

In witness whereof I have hereunto subscribed my name in the presence of two witnesses.

ANDREW W. NELSON.
